FIG. 4

James Overton
BY
Harry Bowen
ATTORNEY

UNITED STATES PATENT OFFICE.

JAMES OVERSON, OF BIG LAKE, WASHINGTON.

COLLAPSIBLE-STAKE LOG BUNK.

1,413,540.

Specification of Letters Patent. Patented Apr. 18, 1922.

Application filed January 30, 1922. Serial No. 532,604.

To all whom it may concern:

Be it known that I, JAMES OVERSON, a subject of the King of Denmark, residing at Big Lake, county of Skagit, and State of Washington, have invented a new and useful Collapsible-Stake Log Bunk; and I do hereby declare that the following is a full, clear, and exact specification, such as will enable others skilled in the art to which it applies to make and use the same.

The invention is a device for holding logs on cars in which the stakes at the ends may be released from the opposite side of the cars.

The object of the invention is to provide log bunks with stakes in their ends pivoted and locked in such a manner that they may be released from the opposite side of the car and when they are released they will swing about the pivot and drop out of the way.

Another object of the invention is to provide a means for locking stakes in the ends of log bunks so that they will be held absolutely rigid in the vertical position and so that they may be released from the opposite side of the car.

And a still further object of the invention is to provide a nut or lugs on the end of the bolt used in log bunks for releasing the stakes which will not be broken off by logs hitting it.

With these ends in view the invention embodies a long frame divided into two sections with small partitions across them, a vertical member pivotally mounted in the opposite end of each section, having a hook on the lower corner of its inner side, a flat plate with a lug on its end to fit into the hook in each section and bolts with a collar and nut on them threaded into the ends of the flat plates and extending through the sections so that they may be turned from the opposite ends of the sections.

Other features and advantages of the invention will appear from the following description taken in connection with the drawings, wherein:

Figure 1 is the side elevation of a car showing the bunks holding the logs.

Figure 2 is a cross section with the side of one of the bunks broken away.

Figure 3 is a cross section on the center-line of one of the sections.

Figure 4 is a cross section on line 4—4 of Figure 2.

Figure 5 is a section showing an alternate arrangement of the means for holding and turning the rod.

In the drawings I have shown my device as it will be used wherein numeral 1 indicates the long frame which is constructed of three plates as shown in Figure 4, the center plate being indicated by the numeral 2 and the two side plates by the numerals 3 and 4. The section between the plates 2 and 3 is similar to the section between the plates 2 and 4 except that they are arranged in opposite directions, therefore I will describe the construction for one section which will be understood to apply to either.

A stake 5 is mounted upon a pin 6 in the end of the frame as shown in Figure 3 and may be made as shown with a hub 7 having a hole 8 in it through which the pin 6 passes, a hook 9 with a recess 10 between it and the hub and a vertical T shaped section projecting upward; or it may be made of structural steel or wood or in any desired manner as long as it will perform the functions hereinafter described.

A flat plate 11 is slidably held between lugs 12 and 13 which project from each side of the section and on one end of this plate is a lug 14 as shown in Figure 3 which has a projection 15 on it to fit into the recess 10 of the stake 5. On the opposite end of the plate 11 is another lug 16 which has a threaded hole 17 in it into which the rod 18 operates and in front of this lug is an opening 19 which allows the rod to pass through the lug to the position shown in Figure 3. The rod 18 extends the entire length of the section and through the opposite end where it has a nut or head 20 on it. This head is constructed in such a manner that it may be gripped by any suitable device for turning the rod. I have shown it in the shape of half of a sphere with two slots 21 and 22 through it at right angles so that a bar or pipe may be placed into the slots to twist the bar. I have shown a collar 23 screwed on to the end of the rod and locked in the position shown by the set screw 24. This collar is held between two partitions 25 and 26 in the section. These partitions may be placed in any desired location in the section and the collar 23 may be held to the rod in any desired manner; or it may be made on the rod as shown in Figure 5 and may be placed at the

end of the section with the end plate 27 forming one of the partitions. When constructed in this manner all of the partitions and the end plate should be open at the top 5 with slots 28 in them as are made in the intermediate partitions 29 shown in Figure 4. In Figure 5 I have also shown an alternate construction for the head of the bolt which shows two prongs 30 connected to a base 31 10 which forms the head of the bolt. It will be seen that a bar or pipe may be placed between these lugs to turn the rod.

In the lower corners of the hook 9 of the stake 5 may be notches 32 to clear the lugs 15 12 as the stake is in the vertical position shown.

It will be understood that other changes may be made in the construction without departing from the spirit of the invention.

20 One of such changes may be in the manner of the construction of the sections as they may be made of structural steel with the lugs 12 and 13 riveted on, another may be in the design of the plate 11 and still another may be in the use of a different means for moving the plate backward and forward.

The construction will be readily understood from the foregoing description. To use the device it will be placed across the top 30 of a car or two trucks, one being placed a short distance from each end and the stakes 5 placed in the vertical position where they will be locked by turning the rod 18 from the opposite side of the car. The logs may 35 then be placed across the bunks and the stakes will hold them on the cars. When it is desired to dump the cars the rods may be turned in a counter-clockwise direction which will move the lugs 15 back to the 40 position shown in dash lines in Figure 3 so that the hook 9 will be free to move upward in the arc indicated by dash lines 33 and the stake will then rotate about the pin 6 until it drops downward so that it will be entirely 45 out of the way and the logs on the bunk may then roll off of the ends. As these stakes are released from the opposite side of the cars this device eliminates any possibility of the person removing the stakes being hurt by 50 the logs rolling off. After the logs have been dumped the stakes may be raised to the position shown and locked by tightening up the bolts.

Having thus fully described the invention,

what I claim as new and desire to secure by 55 Letters Patent is:—

1. A device of the type described embodying a frame constructed in two similar sections arranged opposite to each other; vertical members in the ends of the sections; said vertical members being so arranged that the one in one section will be at one end of the device and the one in the other at the other end of the device; pins for pivotally supporting these members; hooks on the lower 60 corners of these members; other hooks on horizontal plates which fit into the hooks of the vertical members; lugs in the sides of the sections for holding the horizontal plates 65 freely; lugs with threaded holes in them on the opposite ends of the horizontal plates; openings in the plates adjacent to the lugs; a rod with threads on one end extending longitudinally through each section; collars on the rods held between partitions in the sections; and suitable heads on the ends of the rods by which the rods may be turned. 70

2. A collapsible stake log bunk of the class described embodying a frame made in two sections; vertical members in the ends of 80 each section; said vertical members being so arranged that the one in one section will be at one end of the device and the one in the other at the other end of the device; pins for pivotally supporting these members; 85 hooks on the lower side of the vertical members; other hooks slidably mounted in the frames to engage the hooks on the vertical members; and a rod suitably mounted in each section and attached to the hooks in 90 such a manner that they may move the hooks backward and forward.

3. A device of the type described comprising a frame made in two sections with small partitions across the sections; vertical members in one end of each section pivotally mounted on pins; said vertical members being so arranged that the one in one section will be at one end of the device and the one in the other at the other end of the device; 95 hooks on the lower sides of the members; and other hooks slidably mounted in the frames for engaging the former hooks which are constructed in such a manner that they may be drawn into the hooks and moved out of 100 them from the opposite end of the frame. 105
